UNITED STATES PATENT OFFICE.

JAMES A. TILDEN, OF HYDE PARK, ASSIGNOR OF ONE-HALF TO FRANCIS C. HERSEY, OF SOUTH BOSTON, MASSACHUSETTS.

PISTON WATER-METER.

SPECIFICATION forming part of Letters Patent No. 251,971, dated January 3, 1882.

Application filed July 20, 1881. (Model.)

To all whom it may concern:

Be it known that I, JAMES A. TILDEN, of Hyde Park, Norfolk county, State of Massachusetts, have invented an Improvement in 5 Fluid Engines or Meters, of which the following description, in connection with the accompanying drawings, is a specification.

My invention relates to a fluid engine or meter, and is intended as an improvement on the 10 meter formerly invented by me, upon which Letters Patent No. 248,679 were granted October 25, 1881, to which reference may be had.

In my present invention, as in the former, the engine consists of a cylinder containing a 15 main piston itself formed as a cylinder, in which a secondary piston operates, the passages of the said cylinder and pistons being such that one piston acts as a valve to control the operation of the other.

20 My present invention consists in a different arrangement of the said ports, having for its object to insure the more perfect operation of the engine, in which the main piston at the end of its stroke brings passages into the proper 25 relation to admit fluid in one end thereof, and permit it to pass from the other end to cause the secondary piston to make its stroke therethrough, at the end of which the said secondary piston brings its ports into such relation 30 as to admit the actuating-fluid to one end of the main cylinder and permit it to pass from the other end thereof. When the flow of fluid is very slow there is a liability, especially after the ports are somewhat worn, that the main

35 piston will begin to move before the secondary 40 one has wholly completed its movement and fully opened the ports, admitting the fluid to actuate the main piston, so that the said main piston is retarded in its movement. In my 45 present invention I obviate this difficulty by causing the main piston, during its movement, to again admit the fluid to the secondary piston, causing its stroke to be completed with certainty.

50 Throughout the following description the term "main" will be applied to those passages through which the fluid passes to operate the main piston, and the term "secondary" to those passages traversed by the fluid in operating the secondary piston. The main or outer

cylinder is provided with depressions near its ends on the side provided with the inlet for the actuating-fluid, the said depressions being properly arranged to connect the main inlet-port, through which the fluid enters to actuate 55 the main piston, with the secondary inlet-port, through which the fluid enters the main piston to actuate the secondary piston, so that just at the end of the stroke of the main piston the fluid is acting upon both it and the 60 secondary piston, and, owing to the greater area of the main piston, will insure its completing its stroke. After the secondary piston has nearly or wholly completed its stroke and the main piston begins to make its return-stroke, the said depression in the cylinder will 65 connect the secondary inlet-port with the end of the main cylinder that is receiving the actuating-fluid, and consequently the said actuating-fluid will again act upon the second piston, 70 causing it to complete its stroke if it has not already done so. While the secondary piston is thus receiving a second impulse from the actuating-fluid the other end of the main piston, or that from which the fluid was exhausted 75 when the secondary piston made its last stroke, is connected by the other depression in the main cylinder with the end of the main cylinder from which the fluid is being exhausted to 80 permit the movement of the piston, so that in 85 the movement of the secondary piston caused by its second impulse the fluid before it has an exhaust-passage, together with the fluid exhausting before the main piston.

Figure 1 is a vertical longitudinal section on line $x-x$, Fig. 2, of a fluid-engine meter constructed in accordance with my invention; Fig. 2, a vertical section in line $y-y$, Fig. 1, on a plane at right angles to that of Fig. 1, the parts being shown in both figures in the position in which the main piston has just completed its stroke and the secondary piston is 90 about to make a stroke. Fig. 3 is a section on the same plane as that of Fig. 1, the pistons being shown in elevation in a position assumed 95 after the secondary has completed its stroke from the position shown in the first two figures and the main piston has begun its stroke, the fluid being admitted to give a second impulse upon the secondary piston. Fig. 4 is a diagram 100

showing the surface of the main piston developed; and Fig. 5 a similar diagram, showing the surface of the secondary piston developed.

The main or outer cylinder, *a*, is provided 5 with an inlet-passage, *b*, and outlet-passage *c*, located at its sides and at the middle of its length, and is also provided with depressions 2 3 near its ends, on the same side with the inlet-passage *b*.

- 10 The main piston *d*, fitted to reciprocate in the cylinder *a*, is provided with a passage, *e*, through the middle of its side, entering from a depression, *e'*, in the outer surface of the cylinder, sufficiently extended to remain in connection with the inlet-port *b* during the entire stroke of the said piston *d*, and to connect the said inlet-port *b* with the depressions 2 3 of the cylinder at the end of each stroke, respectively, of the said main piston, as shown in Fig. 15. 1. The main piston *d* is also provided with secondary inlet-passages *f f*, which are connected at the end of the stroke of the main piston by the depressions 2 3 and the enlarged port of the opening *e* with the inlet-passage *b*, 20 as shown in Fig. 1, so that the fluid is permitted at the end of the stroke of the main piston to enter the said main piston and operate upon the secondary piston. The main piston is also provided with a main exhaust-passage, *h*, upon 25 the same side with the outlet-passage *c* of the cylinder, and of proper size to remain in connection therewith during the entire stroke of the said main piston, which is also provided with secondary exhaust-passages *i j*, which are 30 properly extended upon its outer surface to be brought into connection with the outlet *c* of the cylinder at the end of the stroke of the main piston, as shown in Fig. 1, where the ports are in proper position to receive fluid 35 through the passage *b*, opening *e*, depression 2, and secondary inlet *f* to one end of the main piston, to operate upon the secondary piston, and to permit the exhaust of the fluid from the other end of the main piston through the 40 secondary exhaust-passage *j* and exhaust-passage *c*.

The secondary piston *k* is made hollow and provided with a main inlet-passage, *l*, properly arranged to remain throughout its stroke in 45 connection with the main inlet-passage *e* of the main piston, so that the fluid always has a free inlet from the passage *b* through the openings *e* and *l* to the interior of the secondary piston, which is also provided with main inlet-ports 50 *m n*, one only of which is shown in Fig. 1, and which are respectively brought in connection with ports *o p* (see Figs. 2 and 3) in the main piston leading to the ends of the main cylinder, and operating as inlet and exhaust ports alter- 55 nately.

As shown in Fig. 2, the port *n* is still in connection with the port *p*, in which position it has permitted the fluid to enter the main cylinder and cause the stroke of the main piston 60 to be made. The secondary piston is also provided with a channel, *r*, in its exterior surface, passing spirally from a position on the same

side with the inlet-port *m*, and nearer the other end of the secondary piston, around the side of the secondary piston adjacent to the outlet-passage *c* of the cylinder to the same side with the inlet-port *n*, and at the opposite end of the secondary piston. The said channel *r* is of such width that it always remains in connection with the main exhaust-port *h*, and it has 70 one of its ends brought into connection with one of the ports *o p* of the main piston at the end of the stroke, by which the other one of the said ports is connected with that one of the inlet-ports *m n* which is adjacent to the other 75 end of the said channel *r*, so that while the fluid is passing from the interior of the secondary piston through the ports *n* and *p*, for instance, to one end of the main cylinder the fluid is passing from the other end of the main 80 cylinder through the port *o*, channel *r*, and passages *h* and *c*, thus causing the main piston to make its stroke, which is shown as just finished in Figs. 1 and 2, and at the end of which the secondary ports *f* and *g* are brought in position to cause the secondary piston to make a stroke, at the end of which the inlet-port *m* will be brought in connection with the port *o* and the channel *r* with the port *p*, to cause the 85 main piston to make its return-stroke. 90

When the fluid is moving very slowly, as may be the case in a water-meter, the main piston may begin to move before the ports *m o* are brought fully into coincidence, and the depressions 2 3 of the cylinder are made of greater length than the spaces between the secondary inlet-ports *f g* and the adjacent ends 95 of the main piston, so that after the main piston has moved a short distance, as shown in Fig. 3, the secondary inlet-port *f* will be connected by the said depression 2 with the end 100 of the cylinder that is receiving fluid through the main inlet-passages *m o*, to thus permit the fluid to again act upon the secondary piston and cause it to complete its stroke. At the 105 same time the secondary inlet-passage *g* at the other end of the main piston will be connected by the depression 3 with the end of the cylinder from which the fluid is passing through the port *p*, channel *r*, and passages *h* and *c*, the 110 said port *g* in this instance acting as a secondary exhaust-port for the time being until the 115 stroke of the secondary piston is completed.

In order to equalize the wear of the surface of the pistons and cylinders, the apparatus is 120 preferably so placed that the said pistons reciprocate in a vertical path, and the heads of the cylinder and main pistons are provided with clearance-spaces *t* to receive the gritty or sedimentary matter that may accumulate during the operation of the machine. 125

A stem or piston-rod, *u*, may be connected with either piston to actuate recording or other mechanism, as desired.

The pistons are prevented from rotating in 130 their reciprocity movements by suitable guides, that of the secondary piston being shown at *w*.

I claim—

1. The main cylinder provided with an inlet-

passage and with internal depressions in the side thereof, combined with the main piston provided with secondary inlet-ports and a depression in its surface in connection with the 5 said inlet-passage throughout its stroke, and acting in co-operation with the said depressions of the cylinder to connect the secondary inlet-ports with the said inlet-passage of the cylinder at definite points in the stroke of the main 10 piston, substantially as described.

2. The cylinder provided with inlet and outlet passages and with the internal depressions all in its sides, combined with the main piston provided with the secondary inlet-ports, and 15 the secondary piston therein, the said ports and depressions being arranged, as described, to connect the interior of the main piston at each end with the corresponding end of the cylinder during a portion of the stroke of the 20 main piston, substantially as and for the purpose set forth.

3. The main cylinder provided with an out-

let-passage, and the main piston therein provided with a main outlet-port in connection with the said passage throughout its stroke, 25 and with ports leading to the main cylinder at either end of the said piston, combined with the secondary piston provided with an external channel always in connection with the said main outlet-port and with main inlet-ports, arranged as described, whereby one of the said main inlet-ports is in communication with the port of the main piston leading to one end of the cylinder, while the corresponding port leading to the other end of the cylinder is in communication with the said external channel, 30 substantially as described.

In testimony whereof I have signed my name to this specification in the presence of two subscribing witnesses.

JAMES A. TILDEN.
